PULL-BACK SPRING FOR SCRAPER TAIL
GATES

Robert G. Le Tourneau, Peoria, Ill., assignor to
R. G. Le Tourneau, Inc., a corporation of California

Application January 16, 1937, Serial No. 120,951

4 Claims. (Cl. 37—126)

This invention relates to scrapers of the type shown in my Patent No. 2,112,105, particularly with respect to the return or pull-back means for the tail gate of the scraper.

In the previous scraper, the tail gate was returned by a series of compression springs which were mounted in spring boxes, one on the frame and the other on the tail gate, and which springs were compressed by the advancing of the tail gate. With this arrangement, a great travel and compression of the springs was required for the springs to have the necessary pulling strength when the tail gate approached a fully retracted position. This consumed considerable power and necessitated the use of a very heavy structure to resist the springs when they were thus greatly compressed.

The principal object of my present invention is to provide an improved and simplified construction for the purpose so arranged that the major power of the spring is available when it is most needed and less tractor power (applied to the power control unit) is required to tension the spring.

A further object is to provide an arrangement for the purpose which utilizes a chain spring of considerably lesser length than was originally required, thus simplifying the apparatus and reducing the cost of construction.

These objects I accomplish by means of such structure and relative arrangement of parts as will fully appear by a perusal of the following specification and claims.

In the drawings similar characters of reference indicate corresponding parts in the several views:

Fig. 1 is a side elevation of a scraper partly in section showing my improved tail gate retracting construction.

Fig. 2 is a fragmentary enlarged longitudinal section showing the tail gate pull-back structure.

Fig. 3 is a fragmentary rear end view of the scraper.

Referring now more particularly to the characters of reference on the drawings, the scraper as a whole is substantially the same as in said co-pending application and comprises longitudinal frame beams 1, a front bowl 2 rigid therewith, a rear bowl 3 slidable in the front bowl, and a tail gate 4 slidably mounted on the beams 1 and movable lengthwise in the rear bowl. The tail gate is pulled forwardly by a cable 5 in the same manner as in the previous structure.

Wheels 6 are disposed rearwardly of the tail gate, the axles 7 of said wheel being supported

at their outer ends on bearings mounted on the lower frame beams 1, and at their inner ends in bearings 8 mounted on a central rearwardly projecting beam 9.

A cross-beam 10 supported at its ends from the beams 1 is disposed above the wheels and is also connected to and braced from the beam 9 by vertical transverse diagonals 11 and by downwardly and rearwardly sloping and transversely converging diagonals 11a.

A rigid compression beam 12, preferably of cylindrical form, extends forwardly and upwardly from the cross beam 10 centrally thereof to a connection with the top of the A frame 13, which projects upwardly from the beams 1 at 15 the front and to which the cable actuated pusher beam 14 is connected, as before. By reason of the above described construction, it will be seen that a rearward pushing movement on the beam 14 is transmitted to the beam 12 and thence to the beam 9 rearwardly of the wheel axle, imparting the desired lifting effect to the scraper as a whole, as in the previous device.

The beam 12 is hollow and its rear portion contains a longitudinal extending helical spring 15. The upper forward end of this spring is engaged by a cap 16 to which one end of a cable 17 is secured. This cable extends through the spring and across the beam 10 and is thence wound over a drum 18. This drum is disposed between 30 the upper face of the drum being tangent to the axis of the spring.

Another cable 19 is connected to the back of the tail gate 4 and extends rearwardly and about a drum 20 from underneath. This drum is formed as a unit with the drum 18 to one side of the same and is arranged in the shape of a spiral cable receiving face or groove, as shown. The cable 19, when the tail gate is retracted, is 40 wrapped about the spiral groove for substantially the full length thereof and pays out from the small end of the drum, as shown in Fig. 2. In this position of the parts, the spring 15 is extended and substantially slack.

When the tail gate is pulled forwardly by the cable 5, the cable 19 is unwound from the drum 20, while the cable 17 winds onto the drum 18, thus placing the spring 15 under compression. The initial compression of the spring, when but 50 little power is necessary to effect this, is practically in direct proportion to the movement of the tail gate, since the drum 18 is practically the same size as the small or inner portion of the spiral groove of the drum 20. The compressing 55

movement of the springs becomes increasingly slow with a constant speed of movement of the tail gate as the cable 19 gradually unwraps from the drum 20 with its ever increasing size. The leverage thus imparted to the spring compressing cable enables the spring to be placed under a great tension with a minimum of power. Also, a relatively great tail gate movement, such as is necessary in a scraper of this type, is translated into a much shorter spring compressing movement and a shorter spring may therefore be used to give the same effect obtained with the previous device.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention, what I claim as new and useful and desire to secure by Letters Patent is:

1. A tail gate pull-back spring motor for an earth working scraper having a bowl, a tail gate movable lengthwise of the bowl and means to pull the tail gate forwardly; said spring motor comprising a compressible helical spring mounted on the scraper, one end of the spring being fixed against movement and said spring being substantially fully extended when the tail gate is in a fully retracted position, a cable drum turnably mounted on the scraper beyond the fixed end of the spring, a cable wound on said drum and extending through the spring and applied to the other end thereof, another cable drum mounted as a unit with the first named drum, said other drum comprising a spiral cable receiving groove, the smallest radius of the spiral being approximately the same as that of the first named drum, and another cable wound on said
- 25 groove and anchored at the large end of the spiral, said other cable being connected to the back of the tail gate and paying out from the small end of the spiral when the tail gate is retracted; the first named cable being arranged
- 30 to be wound onto its drum as said other cable
- 35
- 40
- 45
- 50

is unwound from its drum with the advancing movement of the tail gate.

2. A tail gate pull-back spring motor for an earth working scraper having a bowl, a tail gate movable lengthwise of the bowl and means to pull the tail gate forwardly; said spring motor comprising a drum unit mounted on the scraper, said unit having one drum of constant diameter and another drum having a spiral cable receiving groove, said drums being secured against relative rotation, cables secured at one end to the drums for winding thereabout in opposed directions, the cable for said other drum being secured thereto at the large end of the spiral groove, a normally expanded helical compression spring mounted on the scraper with one end fixed against movement, the cable from said one drum normally being unwound and passing through the spring from the fixed end and secured to the other end thereof, and the cable 20 from said other drum being operatively connected to the tail gate and arranged to be wound onto the spiral groove when the tail gate is in its normal and retracted position.

3. A spring motor comprising a drum unit having one drum of constant diameter and another drum formed with a spiral cable receiving groove, cables secured to the drums for winding thereabout in opposed directions, a helical compression spring mounted substantially tangent to said one drum and fixed against movement at the end adjacent the drum, the cable from said drum passing through the spring from the fixed end thereof and secured to the other end of said spring; and means to mount the spring motor on a scraper having an independently advanced tail gate so that the cable from the other drum may be operatively connected to the tail gate in a direction to cause the spring to be placed under tension by the advancing movement of the tail gate whereby said tail gate will be retracted when the advancing pressure on the tail gate is released.

4. A structure as in claim 1, in which the scraper includes a frame having a rigid hollow compression beam extending substantially tangent to the first named drum; the helical spring being disposed within the beam.

ROBERT G. LE TOURNEAU.
